TEXTILE APPARATUS

Sebastiano Magnano, Andover, Mass., and William G. Abbott, Jr., Milford, N. H., assignors to Magnano Corporation, Lawrence, Mass., a corporation of Massachusetts

Application January 19, 1938, Serial No. 185,716

22 Claims. (Cl. 28—41)

This invention pertains to textile apparatus, especially to machines for associating warp yarns or threads with detached loom elements such, for example, as loom stop-motion drop pins or wires, relating more particularly to apparatus of the general type disclosed in the Patent No. 1,811,206 granted to Sebastiano Magnano June 23, 1931, and is specifically concerned with improved means for stopping the operation of the mechanism in response to certain eventualities, for example, failure of a warp yarn to be properly positioned or failure of the apparatus to deliver a drop wire at the proper time and place.

As pointed out in the patent to Sebastiano Magnano No. 1,811,675, dated June 23, 1931, it is usual to arrange the loom-stop drop wires in banks, and in weaving certain types of goods, for instance rayon, it is necessary to deliver successive wires to the several banks in a predetermined order; for instance, in a six-bank arrangement, it may be required to deliver the wires to the several banks in the following order, namely, to bank 1, bank 3, bank 5, bank 2, bank 4 and bank 6. It is obvious that if the machine fail to deliver a wire at the proper time, the next wire to be delivered must be placed in the bank which failed to receive its intended wire, rather than in the next bank, and accordingly any stop mechanism designed to stop the machine upon failure of a wire to feed properly must act with great rapidity in order to avoid over-travel of the delivery device. Accordingly one object of the present invention is to provide improved stop mechanism responsive to the failure of a wire to feed properly and which will act so quickly and certainly as to ensure delivery of the next successive wire to the proper bank.

In the operation of machines of this type it sometimes happens that a warp yarn breaks or for some other reason is not properly positioned for the reception of the wire as the latter is delivered, and a further object of the present invention is to provide means operative quickly to stop the machine upon such occurrence. In such machines it is usual to drive all of the parts, including the wire delivery means and the warp picking and positioning elements, in timed relation from a single power shaft, and in such an arrangement, no matter how quickly the stop mechanism may act in response to the breakage of a yarn, it is possible that the warp positioning elements may advance slightly while the mechanism is stopping. Accordingly, before starting again, the position of elements must be turned back in order properly to receive the pieced-up

yarn. However, it is undesirable to try to reverse the wire delivery mechanism, and a further object of the invention is to provide means whereby the warp picking and positioning elements may be turned back slightly without affecting the wire delivery means.

In the machines of this type, as described in the above-noted patents, it is usual intermittently and automatically to advance the mechanism across the sheet of warps so as to permit it to operate upon successive groups of warps. A further object of the present invention is to provide improved simple and reliable means operative in response to the exhaustion of the warps constituting such a group to initiate movement of the apparatus as a whole to a new position where it may act upon the next successive group of warps.

Other and further objects and advantages of the invention will be made manifest in the following more detailed description and by reference to the accompanying drawings, in which

Fig. 1 is a fragmentary side elevation, partly in vertical section, showing so much of a drop wire applying machine of the general type of that of my Patent No. 1,811,206 as is necessary to illustrate the improved stop mechanism and adjunctive parts constituting the present invention;

Fig. 1^a is a fragmentary detail, in side elevation, to larger scale, showing certain parts illustrated in Fig. 1;

Fig. 2 is a fragmentary plan view of the mechanism of Fig. 1;

Fig. 3 is a vertical section, to larger scale, substantially on the line 3—3 of Fig. 1;

Fig. 4 is a fragmentary vertical section substantially on the line 4—4 of Fig. 1;

Fig. 5 is a fragmentary plan view of some of the parts shown in Fig. 4;

Fig. 5^a is a fragmentary section on line 5^a—5^a of Fig. 5;

Fig. 5^b is a fragmentary section on line 5^b—5^b of Fig. 5^a;

Fig. 6 is a fragmentary vertical section substantially on the line 6—6 of Fig. 1;

Fig. 7 is a fragmentary vertical section substantially on the line 7—7 of Fig. 1; and

Fig. 8 is a section, to large scale, transversely of the drive shaft, illustrating an arrangement whereby the warp positioning elements may be moved back without reversing the wire feed.

Referring to the drawings, the numerals 14^a and 15^a indicate parallel rails such as the rails similarly designated in the above Patent No. 55

1,811,206. These rails are intended to rest upon the loom frame and to support the drop-wire delivering mechanism while it is performing its intended function. As here illustrated, each rail 5 comprises a longitudinal rack portion R (Fig. 2). The machine is supported on the rails by means of rollers, such as the rollers 5 and 6, designed to travel lengthwise of the rails 14^a and 15^a. One of the rolls 5 and 6 at each end of the machine is furnished with a peripherally toothed portion or pinion which meshes with the corresponding rack R. These pinions engage idler pinions 5^a and 6^a (Fig. 1) which in turn mesh with pinions 7 and 7^a, respectively, fixed to a shaft 8 which corresponds in function to the shaft 8 of my prior Patent No. 1,811,206. This shaft 8 is journaled at opposite ends in the end members 1 and 2 of the machine frame, said end members being rigidly united by the longitudinally extending front and rear rails 3 and 4, respectively (Fig. 2). The upper edges of the rails 3 and 4 provide a track or guideway along which travel flanged rollers (not shown) supporting a movable carriage C which, in general, is similar in construction and function to the magazine supporting carriage of my aforesaid patent, said carriage comprising spaced parallel side walls 3^a and 4^a and end members 1^a and 2^a (Fig. 2).

A motor M mounted on the machine frame 30 drives speed reduction gearing (not shown) in a box 15 in which is journaled the longitudinally extending shaft 16. As here illustrated, this shaft is provided with a cam 17 having a groove 18 which receives a cam follower 19 mounted on the carriage C whereby the rotation of the shaft 16 causes the carriage to move back and forth along the rails 3 and 4.

The carriage C supports the drop-wire magazine (not shown), which may be like that of Patent No. 1,811,206 or otherwise, as desired, together with the corresponding accessory elements and mechanism (including rolls herein-after more fully described) necessary to deliver wires one by one in properly timed relation and in position to be received by a properly disposed warp yarn.

The machine frame has spaced depending brackets 20 and 21 (Fig. 1) which carry supporting members 22 and 23 or the equivalent from which project the fingers 24 corresponding in number to the number of banks of wires to be placed on the warps and functioning like the fingers 261 of Patent No. 1,811,206. The brackets 20 and 21 also support transverse bridge members 25 and 26 upon which are mounted sets of warp manipulating elements corresponding in construction, arrangement and function to the warp manipulating elements of my aforesaid patent. Among such elements is the rocking warp positioner 27 (Fig. 3). The warp positioner 27 is mounted to rock on a fixed stub shaft 28 projecting from the support 25 and is rocked by appropriate connections (not shown) once for each drop wire delivered. This warp positioner 27 carries a long projecting pin 29 substantially parallel to the shaft 28 and which projects to the left of the positioner as viewed in Fig. 1.

The gearing in the box 15 includes a clutch (not shown) whose parts may be relatively separated to stop the drive of the carriage and the other parts of the machine. The operation of this clutch is controlled by a shaft 30 (Fig. 3) extending from front to rear of the machine and provided at its forward end with an actuating handle 31. The shaft 30 is also provided with a

laterally projecting stud 32 having an inclined cam face 33 engageable by a roller 34 carried by an arm 35 fixed to a sleeve 36 turning on the shaft 8. By engagement of the roll 34 with the cam face 33 the shaft 30 may be rocked and the clutch parts disengaged, thereby to stop the machine.

Mounted on the shaft 8 is a lever 37 (Figs. 1 and 5) to the lower end of which is connected a link 38 (Fig. 3) which is constantly reciprocated while the machine is running by means (not shown) within the gear box 15, thereby constantly rocking the lever 37 from front to rear. The lever 37 is bifurcated at its upper end, its legs being shaped to form disk-like journal members 40 (Fig. 5^a) having aligned journal openings for the reception of shaft 8. Between the legs is disposed a ratchet wheel 39 which is fixed to the shaft 8. At opposite sides of the ratchet wheel 39 are disposed collars 40^a which turn on reduced portions of the disks 40, the collars having projecting segmental arms 41 between which is fixed a weight 42 which tends to turn the collars in a clockwise direction, as viewed in Fig. 4, so far as is permitted by a fixed stop. A curved guard plate 43, substantially concentric with the ratchet 39, projects downwardly from the weight and is normally interposed between the teeth of the ratchet and a pawl 44 mounted on the lever 37. During the normal operation and so long as warps are positioned in readiness to be picked, the pawl is idle, being held out of contact with the ratchet by the guard plate 43, but when it becomes necessary to move the machine along the sheet of warps to enable it to manipulate the warps of a new group, the guard plate 43, which normally follows the lever 37 as the latter swings, is held stationary as hereinafter more fully described, and the pawl slips off of its free extremity and operatively engages teeth of the ratchet 39, thereby by turning the shaft 8 and advancing the entire mechanism along the rails 14^a and 15^a.

The drop-wire delivery mechanism includes a pair of intermittently acting feed rolls 45 and 46 (Fig. 1), the roll 46 being mounted in fixed bearings in a bracket 47 supported by the carriage while the roll 45 is journaled in a frame which rocks about a shaft 48 supported by the bracket 47. The frame which carries roll 45 is urged in a clockwise direction by a spring (not shown) 49 and has an upwardly extending arm 50 which has pin and slot connections at its upper end with the shorter arm 50 (Figs. 1 and 3) of a bell crank lever pivotally supported by the carriage and having a long bent arm 51 whose free end overlies a slidably, normally stationary transmitter 52 freely movable along the upper edge of the frame member 4. This transmitter slide 52 has notches 53 in its upper edge for the reception of a downwardly directed dog 54 at the end of the lever arm 51. The notches 53 have vertical end walls, but a second, fixed plate 55, parallel to plate 52, has elongate notches 56 having inclined end walls constituting cams for raising the dog 54 out of any notch 53 with which it may be engaged after the plate 52 has moved far enough to operate the stop devices, as hereinafter more fully described, but before the engagement of the dog and slide 52 can block the normal travel of the carriage.

The number of notches 53 corresponds to the number of banks of drop wires to be placed on the warp, the notches being equally spaced and so arranged that whatever position the carriage may occupy when a drop wire fails to feed prop-

erly, the dog 54 will engage a notch 53 and cause the machine to stop before the carriage can have moved to the wire delivery position corresponding to the next bank. Thus, whereas in the machine of Patent No. 1,811,675 the carriage might continue to move through a substantial distance, after failing to deliver a wire, before stopping and thus, when again started, fail to place wires in intervening banks, the present arrangement makes it impossible to skip a bank when restarting the machine after a stop resulting from failure to deliver a wire.

The sleeve 36 is provided with an arm 55 (Figs. 1 and 4) at the end opposite to that at which the arm 35 is mounted, and the arm 55 is furnished at its lower end with a substantially vertical abutment shoulder 56 at its rear side (Fig. 4). A motion transmitting arm 57 is pivotally supported by the lever 37 with its free end normally disposed below the shoulder 56. A lifter arm 58^a normally underlies the free end of arm 57, the arm 58^a being fixed to a rotary shaft 58 journaled in bearings carried by the frame member 4 and extending parallel to the shaft 8. The shaft 58 is provided with a pair of oppositely directed, normally horizontal actuating arms 59 and 60 (Fig. 7).

A bell crank lever having a substantially horizontal short arm 61 (Fig. 1) is pivotally mounted on the bracket 20, and the lever arm 61 carries a pair of horizontal spring fingers 62 and 63 (Figs. 1 and 7) which overlie and underlie respectively the arms 59 and 60 of the shaft 58. This bell crank lever also has an upwardly directed arm 64 whose upper end engages a notch in the lower edge of the slide member 52.

Pivotedly supported upon the frame member 4 is a lever 65 (Figs. 1 and 6) having at its left-hand end, as viewed in Fig. 1, an abutment block 66 (Fig. 6) which at times may be lifted so as to be interposed between the front face of the frame member 4 and a yoke 67 which unites and projects from the collars 40. When this abutment block is so interposed between the members 4 and 67, it limits rocking of the collars relatively to the lever 37, thus holding back the guard plate 43 and allowing the pawl 44 to act on the ratchet wheel 39, thereby to turn the shaft 8 and advance the machine along the rails 50 as above referred to.

The lever 65 has an arm 68 to which is connected one end of a wire 69. The lower end of this wire is connected to a lever 70 (Fig. 6) mounted to swing on the stub shaft 28 above referred to, the lever 70 being normally held in a substantially horizontal position by a light spring or weight. A detector arm 72 (Fig. 3) is also mounted on the shaft 28 and is urged in a clockwise direction by a spring (not shown), but normally follows the movement of the warp positioner 27 since the arm 72 overlies the pin 29 which projects from the positioner as above described. When the warp positioner is in its upper position, it holds the arm 72 up in the full line position shown in Fig. 6, but each time the member 27 moves downwardly the detector arm 72 is permitted to drop. If its free end then engages warps W (Fig. 6) properly positioned at the advancing or front side of the machine to be manipulated by the warp-positioning elements, it is stopped before a laterally projecting pin 72^a, carried by the arm 72, engages the arm 70. However, if no warps are present, the end of the arm 72 moves down to the broken line position of Fig. 6, and its pin 72^a engages the lever

70 and rocks the latter downwardly, as shown in Fig. 6. The wire 69 is thereby pulled downwardly, thus rocking lever 68 whereby the abutment block 66 is positioned to limit movement of the member 67. The pawl 47 is thus allowed to act and the machine is shifted along the rails 14^a and 15^a until a new group of warps is available for picking and for holding the detector arm 72 in its upper inoperative position.

In order to stop the machine if a warp yarn breaks or is absent from wire-receiving position (even though the machine be properly located with reference to a group of warps) a feeler finger 73 (Fig. 4) is provided. This finger is mounted to swing on the shaft 28 and is normally urged in a clockwise direction (Fig. 4) by a spring or weight but is controlled in its movements by the pin 29 projecting from the yarn positioner 27. A bell crank lever is also pivoted to swing on the shaft 28 and comprises a normally horizontal arm 74 which is disposed in the path of a pin 75 projecting laterally from the feeler 73. The bell crank has a second arm 76 to which is attached one end of a wire 77; the other end of the wire 77 is connected to an arm 78 (Fig. 4) fixed to the shaft 58. The feeler 73 is raised and lowered by the pin 29. If, in its descent, its end engages a warp yarn W' properly positioned for picking (and supported for this purpose by a pair of parallel spaced members 79) the feeler is arrested, but if, on the other hand, no warp yarn is present, the feeler continues to drop;—its pin 75 engages lever arm 74 and rocks the arm 76 downwardly, and the wire 77 is thereby pulled and thus rocks the shaft 58. The arm 58^a, carried by the shaft 58 as above described, is thereby raised and lifts the motion-transmitting lever 57 up far enough to contact the abutment shoulder 56 as the lever 37 rocks forwardly, the lever 57 thus being interposed between the parts 37 and 56. Thus the sleeve 36 is rocked and with it the arm 35 which in turn rocks the cam stud 32 and turns the clutch shaft 30, thereby stopping the machine. If the slide 52 should be actuated when lever 57 is directly below the end of arm 55, one or the other of fingers 62 or 63 will yield, thus avoiding breakage of parts.

The wire delivery feed and the warp picking and positioning devices are driven in timed relation by a drive shaft 12 (Fig. 8) actuated by gearing (not shown) in the box 15. The wire delivery feed receives its motion from shaft 12 through suitable connections including a gear 79 (Fig. 8) keyed to an enlarged portion 80 of the shaft 12. The key 81 is fixed in the part 80 but the keyway 82 in the gear is widened so as to permit lost motion between the parts 79 and 80. When the parts are turning in the normal or forward direction indicated by the arrow (Fig. 8), the wire feed devices are driven in accurately timed relation to the warp positioning elements which are driven positively by the shaft 12 regardless of the direction of rotation of the latter, but if it become necessary to reverse the shaft 12 slightly in order accurately to set the warp-positioning elements, this may be done without reversing the wire delivery mechanism by reason of the freedom of the key 81 to move backwardly in the keyway 82.

If, during the operation of the machine, a wire 70 fail to feed down between the rolls 45 and 46 at the proper time, the rolls abnormally approach and the arm 49 is swung so as to drop the dog 54 far enough to engage one of the notches 53 as the carriage moves in one direction or the other.

When the dog enters any one of the notches, the continued movement of the carriage causes the transmitter slide 52 to move longitudinally in one direction or the other, thus swinging lever arm 64 and causing one or the other of the spring fingers 62 or 63 to engage one or the other of the arms 59 or 60, respectively. The shaft 58 is thereby rocked so as to raise the arm 58a and thus lift motion-transmitting lever 57 high enough to engage abutment shoulder 56 as the lever 37 is rocked rearwardly, thus turning the sleeve 36 and actuating the clutch shaft 30 as above described to stop the machine immediately and before the carriage can move to the next wire-delivery position.

By reason of the construction above described it is manifest that the machine will be moved along the rails 14a and 15a automatically in response to exhaustion of a given group of warps and thus placed in readiness for manipulating a new group of warps. Furthermore, it is apparent that upon failure of the machine to deliver a drop-wire properly or upon absence of a warp yarn, either by breakage or otherwise, from the position which it should occupy to receive a drop-wire, the machine will be very quickly brought to rest so that overtravel and improper subsequent operation is substantially prevented.

While a certain desirable embodiment of the invention has herein been illustrated by way of example, it is to be understood that the invention is not limited to this precise embodiment but is of broader application and inclusive of all equivalents and substitutions of parts such as fall within the scope of the appended claims.

We claim:

1. A machine of the class described including a magazine carriage provided with wire delivery means, warp separating and positioning means, and driving means including a clutch and a clutch release member, characterized in having means including a normally moving part for actuating the clutch release member and in having means which moves into the path of said normally moving part upon failure of the wire delivery means to place a wire in position for engagement by the warp, thereby to transmit movement of said normally moving part to the clutch release member and thus stop the machine.
2. A machine of the class described including wire delivery means, warp separating and positioning means, and driving means including a clutch and a clutch release member, characterized in having means including a normally moving part for actuating the clutch release member and in having means which moves into the path of said normally moving part upon failure of the warp positioning means to place a warp in position for engagement by a wire thereby to transmit movement of said normally moving part to the clutch release member and thus stop the machine.
3. In combination in a machine of the class described having driving means including a clutch and a clutch release member, wire delivery means, warp separating and positioning means, and means for actuating the clutch release member including a normally moving part, and means which moves into the path of said part upon failure of the wire delivery or warp positioning means respectively to place a wire or warp in position for engagement with the other thereby to transmit movement of said normally moving part to the clutch release means.
4. In combination in a machine of the class described having driving means including a clutch

and a clutch release member, wire delivery means, warp separating and positioning means, and means for actuating the clutch release member including independently acting control members, one of which moves from a normal position in response to the failure of the wire delivery means to initiate delivery of a wire and the other of which moves to an abnormal position in response to failure of the separating and positioning means to place a warp in wire-receiving position.

5. In combination in a machine of the class described having driving means including a clutch and a clutch release member, wire delivery means, warp separating and positioning means, and means for actuating the clutch release member including a bodily movable roll which is normally held in inoperative position by a wire on its way to the delivery point, and a feeler which is normally held in operative position by a warp properly disposed to receive a wire, said roll and feeler moving to abnormal positions in response to absence of a wire or warp, respectively, and connections actuated by said roll or feeler, respectively, in so moving to abnormal position for actuating the clutch release means.

6. In combination in a machine of the class described having a frame movable transversely of the warp threads, wire delivery means supported by the frame and means operative intermittently to move the frame, said frame-moving means comprising a ratchet wheel, a constantly oscillating pawl, guard means normally preventing the pawl from operatively engaging the ratchet wheel, a detector device sensitively responsive to the absence of warp threads in position to receive drop wires, and means actuatable by said detector device to move the pawl guard out of operative position.

7. In combination in a machine of the class described having a frame movable transversely of the warp threads, wire delivery means supported by the frame and means operative intermittently to move the frame, said frame-moving means comprising a ratchet wheel, a constantly rocking support coaxial with the ratchet wheel, a pawl carried by the support, a guard normally moving with the support and normally operative to prevent contact of the pawl with the ratchet wheel, an abutment operative at times to prevent movement of the guard with the support thereby to permit the pawl to overrun the guard and engage the ratchet, and abutment actuating means comprising a detector movable in response to absence of warp threads from warp separating position, and connections between the detector and the abutment.

8. In a machine for applying drop-wires to warp threads, said machine being of that kind in which a magazine carriage is arranged to move in a direction substantially parallel to the warp threads, said carriage supporting means for delivering drop-wires one by one for deposit upon the warp threads, carriage drive means operative to move the carriage from one predetermined position to another longitudinally of the warp threads thereby to enable the wire delivery means so to deposit the wires as to form a plurality of distinct banks, and including stop means operative to stop the carriage drive upon failure of the wire delivery means to effect delivery of a wire at the proper time, characterized in that the stop means includes a normally stationary part, and means for immediately imparting movement from the carriage to said part whenever the wire delivery means fails to function.

9. In a machine of the class described including a magazine carriage provided with wire delivery means, carriage drive means operative to move the carriage from one predetermined wire-delivery position to another thereby to cause the delivery means to deposit wires in distinct banks, in combination, stop means operative, in response to failure of the wire delivery means to deliver a wire to any of said banks, to stop the carriage before it reaches the delivery position corresponding to the next bank.
10. In a machine of the class described including a magazine carriage provided with wire delivery means, carriage drive means operative to move the carriage from one predetermined wire-delivery position to another thereby to cause the delivery means to deposit the wires in distinct banks, stop means operative immediately to stop the carriage whenever the wire-delivery means fails to function, said stop means comprising a normally stationary but movable part, and means responsive to failure of the wire-delivery means to clutch said part to the carriage before the carriage reaches the next wire-delivery position.
11. In a machine of the class described including a magazine carriage provided with wire delivery means, carriage drive means operative to move the carriage from one predetermined wire delivery position to another thereby to cause the delivery means to deposit wires in distinct banks, and stop means operative to stop the carriage regardless of its direction of movement whenever the wire delivery means fails to deliver a wire to one of said banks, the stop means comprising a driving member which moves with the carriage, and a normally stationary but movable transmitter having a plurality of spaced elements corresponding in number to the number of banks of wires to be formed, said driving member being constructed and arranged to engage one or another of said spaced elements dependent upon the position of the carriage and thereby to impart operative movement to the transmitter in the interval during which the carriage moves from one wire delivery position to the next.
12. In a machine of the class described including a magazine carriage provided with wire delivery means, carriage drive means operative to move the carriage from one predetermined position to another thereby to cause the delivery means to deposit the wires in distinct banks, and in combination therewith stop means operative to stop the carriage whenever the wire delivery means fails to function, said stop means comprising a normally stationary slide member, and means, responsive to failure of the wire delivery means, to cause said slide member immediately on such failure to partake of the movement of the carriage regardless of the direction of the latter, and thereby stop the machine.
13. In combination in a machine of the class described including a magazine carriage provided with wire delivery means, carriage drive means operative to move the carriage from one predetermined position to another thereby to cause the delivery means to deposit the wires in distinct banks, and stop means operative to stop the carriage whenever the wire delivery means fails to function, said drive means comprising a clutch device, and clutch release means actuatable by the carriage at any of a plurality of positions of the latter and regardless of the direction of movement of the carriage, in response to failure of the wire delivery means.
14. In combination in a machine of the class described including a magazine carriage provided with wire delivery means, carriage drive means operative to move the carriage from one predetermined position to another thereby to cause the delivery means to deposit the wires in distinct banks, and stop means operative to stop the carriage whenever the wire delivery means fails to function, the carriage drive means including a clutch, said stop means comprising clutch release means including a rock member, and means actuated by the carriage, in response to failure of the wire delivery means, to rock said member so as to release the clutch, regardless of the direction of movement of the carriage, in the interval during which the carriage moves from one delivery position to the next.
15. In combination in a machine of the class described including a magazine carriage provided with wire delivery means, carriage drive means operative to move the carriage from one predetermined position to another thereby to cause the delivery means to deposit the wires in distinct banks, and stop means operative to stop the carriage whenever the wire delivery means fails to function, and carriage drive means including a clutch, said stop means comprising a normally stationary slide member, means for imparting movement to the slide member from the carriage, and clutch release means actuated by said slide member to release the clutch regardless of the direction of movement of said slide from its normal stationary position, and while the carriage is moving from one wire delivery position to the next.
16. In combination in a machine of the class described including a magazine carriage provided with wire delivery means, carriage drive means operative to move the carriage from one predetermined position to another thereby to cause the delivery means to deposit the wires in distinct banks, and stop means operative to stop the carriage whenever the wire delivery means fails to function, the carriage drive means including a clutch and the wire delivery means including an actuating part which moves from normal position upon failure of the delivery means to effect delivery of a wire, and carriage actuated means operative to release the clutch upon movement of said actuating part from normal position.
17. In combination in a machine of the class described including a magazine carriage provided with wire delivery means, carriage drive means operative to move the carriage from one predetermined position to another thereby to cause the delivery means to deposit the wires in distinct banks, and stop means operative to stop the carriage whenever the wire delivery means fails to function, the carriage drive means including a clutch and the wire delivery means including an actuating part which moves from a normal position upon failure of the delivery means to effect delivery of a wire, a normally stationary transmitter, means controlled by said actuating part for imparting movement to the transmitter from the carriage, and connections between the transmitter and clutch operative to release the latter regardless of the direction of movement of the carriage.
18. In combination in a machine of the class described including a magazine carriage provided with wire delivery means, carriage drive means operative to move the carriage from one predetermined position to another thereby to cause the delivery means to deposit the wires in distinct banks, and stop means operative to stop the carriage whenever the wire delivery means fails to function, the carriage drive means including a clutch, said stop means comprising clutch release means including a rock member, and means actuated by the carriage, in response to failure of the wire delivery means, to rock said member so as to release the clutch, regardless of the direction of movement of the carriage, in the interval during which the carriage moves from one delivery position to the next.

riage whenever the wire delivery means fails to function, the carriage drive means including a clutch and the wire delivery means including an actuating part which moves from a normal position upon failure of the delivery means to effect delivery of a wire, a normally stationary transmitter, a rock shaft, a clutch release lever secured to the rock shaft, oppositely directed arms fixed to the rock shaft, a lever provided with yieldable, motion transmitting fingers overlying and underlying respectively said oppositely directed arms, said lever having an arm operatively connected to the transmitter, and means operated by said actuating part for connecting the transmitter to the carriage.

19. In combination in a machine of the class described including a magazine carriage provided with wire delivery means, carriage drive means operative to move the carriage from one predetermined position to another thereby to cause the delivery means to deposit the wires in distinct banks, and stop means operative to stop the carriage whenever the wire delivery means fails to function, the carriage drive means including a clutch and the wire delivery means including an actuating part which moves from normal position upon failure of the delivery means to effect delivery of a wire, a normally stationary, slidable transmitter, and means actuated thereby for releasing the clutch, said transmitter having spaced notches corresponding in number to the number of banks of wires to be formed, a dog mounted on the carriage, and means operative by the actuating part to engage the dog with one of the notches of the transmitter thereby to cause the latter to partake of the movement of the carriage.

20. In combination in a machine of the class described including a magazine carriage provided with wire delivery means, carriage drive means operative to move the carriage from one predetermined position to another thereby to cause the delivery means to deposit the wires in distinct banks, and stop means operative to stop the carriage whenever the wire delivery means fails to

function, the carriage drive means including a clutch and the wire delivery means including an actuating part which moves from a normal position upon failure of the delivery means to effect delivery of a wire, a normally stationary, slidable transmitter, and means actuated thereby for releasing the clutch, the transmitter having therein a notch having abrupt end walls, a dog engageable with said notch thereby to connect the transmitter to the carriage, and cam means operative automatically to release the dog from the transmitter notch after a predetermined movement of the transmitter.

21. In combination in a machine of the class described including wire delivery devices and warp positioning devices and drive means for the respective devices, said drive means comprising a shaft having thereon a relatively movable part, positive connections between the shaft and the warp delivery means whereby to drive the latter regardless of the direction of rotation of the shaft, connections between said relatively movable part and the wire manipulating devices whereby to drive the latter, and means connecting said relatively movable part to the shaft constructed and arranged to permit lost motion between said part and the shaft so as to allow slight reverse rotation of said part relatively to the shaft.

22. In combination in a machine of the class described including wire delivery devices and warp manipulating devices and drive means for the respective devices, said drive means comprising a shaft having thereon a relatively movable gear, positive connections between the shaft and the warp delivery means whereby to drive the latter regardless of the direction of rotation of the shaft, connections between the gear and the wire manipulating devices whereby to drive the latter, a key fixed to the shaft, and a keyway in the gear for the reception of the gear, the keyway being wider than the key thereby to permit slight reverse rotation of the gear relatively to the shaft.

SEBASTIANO MAGNANO.
